M. ZIELINSKI.
RAIL JOINT.
APPLICATION FILED NOV. 28, 1921.

1,410,983.

Patented Mar. 28, 1922.

UNITED STATES PATENT OFFICE.

MICHAEL ZIELINSKI, OF PITTSBURGH, PENNSYLVANIA.

RAIL JOINT.

1,410,983.

Specification of Letters Patent. Patented Mar. 28, 1922.

Application filed November 28, 1921. Serial No. 518,164.

To all whom it may concern:

Be it known that I, MICHAEL ZIELINSKI, citizen of Poland, residing at Pittsburgh, in the county of Allegheny and State of Pennsylvania, have invented certain new and useful Improvements in Rail Joints, of which the following is a specification.

This invention relates to a rail joining means for use on railroad tracks and it has for an object to provide a simple and inexpensive device for securing the ends of the rails together.

For further comprehension of the invention, and of the objects and advantages thereof, reference will be had to the following description and accompanying drawings, and to the appended claims in which the various novel features of the invention are more particularly set forth.

Fig. 1 of the drawings is a detail perspective view showing the application of my improved device to a track rail, one of the fish-plate elements being shown cut off flush with the rail joint.

Fig. 2 is a transverse sectional view through a rail, showing my improved fastening device in place thereon.

Fig. 3 is a detail perspective view of one of the fish-plate elements.

Fig. 4 is a detail perspective view of the other fish-plate element.

Fig. 5 is a horizontal sectional view showing a modified arrangement.

In the drawings the reference numeral 10 indicates an end portion of a track rail which is adapted to be secured to an adjacent rail end by my improved fastening means. My improved fastening means comprises, briefly speaking, a pair of elements adapted to overlap the rail ends on opposite sides thereof. One of said elements I term a chair-plate element and the other I term a fish-plate element.

The former of these elements comprises a metal plate bent to present a horizontal base portion 12 adapted to engage under the base flange of the rail to support the latter, and a vertical portion 13 adapted to fit against the web of the rail, these parts 12, 13 being

50 united by an inclined element 14 which fits over the base flange of the rail on one side of the latter. At its top the vertical portion 13 is turned outwardly as at 15 to fit under one side of the tread element of the rail.

55 The fish-plate element is formed complementary to the chair-plate element and com-

prises a main vertical portion 18 adapted to fit against the web of the rail, and upper and lower offset flanges 19 and 20 are adapted to engage under the tread and over the base flange respectively, of the rail.

The fish-plate element has a series of longitudinally spaced tongues struck inwardly from its main vertical part. Two of these tongues may be rolled to the cylindrical 65 form shown at 21, the others being left flat as shown at 22, the cylindrical tongues being exteriorly screw threaded to provide bolts projecting from the fish-plate element.

The chair-plate element is formed with 70 cylindrical and slotted openings, 23 and 24 respectively, to receive the cylindrical and flat tongues, it being understood that the rail ends will have corresponding apertures.

From the side of the horizontal base portion 12 of the chair-plate element, opposite to that to which the inclined part 14 connects, a series of tongues 25 project, while the lower edge of the fish-plate element is formed with registering notches 26. 75

In applying my improved fastening device to the ends of rails the chair-plate element is first inserted in place with its base portion 12 projecting under the rail ends and its other portions fitting snugly against the 85 rail ends. The fish-plate element is then fitted against the rail ends in registry with the chair-plate element, the tongues 21 and 22 extending through the apertures 23 and 24 in the chair-plate element, the tongues 25 90 on the base portion 12 engaging in the notches 26 in the lower edge of the fish-plate element. Nuts 28 are then screwed on the threaded tongues 21, while the ends of the other tongues are bent over to lie against the 95 vertical part 13 of the chair-plate element as indicated at 22'. With my improved rail joining means the rail ends are securely locked against displacement both vertically and horizontally, while the use of supplementary bolts is obviated. 100

In the arrangement shown in Fig. 5 I provide the fish-plate element 18' with cylindrical tongues 21' similar to the tongues 21, and with flat tongues 22' which are somewhat longer than the tongues 22. These tongues 22' have openings in their ends through which the cylindrical tongues 21' project when the flat tongues are bent backward on the chair-plate element 13', the nuts 110 28 being screwed down upon these tongues 22'.

Having thus described my invention what I claim as new and desire to protect by Letters Patent of the United States is as follows:—

- 5 1. A rail joining device comprising a pair of plates adapted to engage the web of the rail on opposite sides thereof, a plurality of integral tongues projecting from one plate, certain of said tongues being circular in cross section and the others flat, the other plate having complementary apertures formed therein to receive the said tongues.
- 10 2. A rail joining device comprising a pair of plates adapted to engage the web of the rail on opposite sides thereof, a plurality of integral tongues projecting from one plate, certain of said tongues being circular in cross section and the others flat, the other plate having complementary apertures formed therein to receive the said tongues, one of said plates having an integral extension adapted to project under the rail.
- 15 3. In combination with a track rail, a pair of plates engaging the web thereof on opposite sides, integral tongues projecting from one plate through the rail and the other plate, certain of said tongues being circular in cross section and exteriorly screw threaded, the other tongues being flat, said flat tongues having angularly projecting extremities in contact with the other plate, and nuts threaded on the cylindrical tongues.
- 20 4. In combination with a track rail, a pair of plates engaging the web thereof on opposite sides, integral tongues projecting from one plate through the rail and the other plate, certain of said tongues being circular in cross section and exteriorly screw threaded, the other tongue being flat, said flat tongues having angularly projecting extremities in contact with the other plate, and nuts threaded on the cylindrical tongues, said last mentioned plate having an integral

base portion projecting under the base-flange of the rail.

5. In combination with a track rail, a pair of plates engaging the web thereof on opposite sides, integral tongues projecting from one plate through the rail and the other plate, certain of said tongues being circular in cross section and exteriorly screw threaded, the other tongues being flat, said flat tongues having angularly projecting extremities in contact with the other plate, and nuts threaded on the cylindrical tongues, said last mentioned plate having an integral base portion projecting under the base-flange of the rail, said first plate having its lower portion extended outwardly over the base-flange of the rail and formed with a plurality of notches on its lower edge, said base portion having integral tongues engaging in the said notches.

6. A rail joining device comprising a pair of plates adapted to engage the web of the rail on opposite sides thereof, a plurality of integral tongues projecting from one plate, certain of said tongues being circular in cross section and the others flat, the other plate having complementary apertures formed therein to receive the said tongues, one of said plates having an integral extension adapted to project under the rail, said base portion having tongues projecting from the edge thereof, the other plate having its lower portion extended laterally and formed with notches adapted to receive the last mentioned tongues.

In testimony whereof I have affixed my signature.

MICHAEL X ZIELINSKI.
